UNITED STATES PATENT OFFICE.

CLAUD E. FULLER, OF NEW YORK, N. Y., ASSIGNOR TO NEW YORK BRICK HANDLING CORPORATION, OF NEW YORK, N. Y., A CORPORATION OF NEW YORK.

DRIER.

Application filed August 9, 1926. Serial No. 128,041.

My present invention relates to drying apparatus and more particularly to an improved pipe rack drier for brick and the like.

- 5   In existing types of pipe rack driers, the source of heat for drying the brick is derived entirely from the steam which is carried in the pipes of the racks which support the pallets of brick. The air which enters the drier, either coming down through the monitor at the cool end or the numerous cracks of the building, is caused to circulate by reason of being heated by the pipe racks themselves. As these pipe racks are 10 of considerable length, varying from 75' to 120' long, and as the pipes themselves are of comparatively small diameter, and as they are supporting pallets of wet, cold brick when the steam is admitted to the racks, 15 the steam condenses quite rapidly and heats up the pipes and surrounding air at a comparatively slow rate. As a result of this action, the inlet end of the drier, that is, the end of the drier where steam is admitted to 20 the pipe racks, becomes heated a considerable length of time before the opposite or outlet end, for the steam and water of condensation must travel the length of the pipe racks to the outlet. The air at the inlet end, 25 which becomes heated by contact with the pipes of the pipe rack drier, rises practically vertically and passes out through the monitors, and as it is, of course, necessary to replace this air and as the outlet end of 30 the drier is still cool or practically of a uniform temperature from top to bottom, and as the monitors have fixed openings, the easiest path for the air to enter is to come down through the monitor at the cool end 35 and travel lengthwise in the drier to fill the space left vacant by the rising warm air. Because of the construction of the usual drier building, this action goes on mostly in the conveyor space between the bricks and 40 very little, if any, heated air passes over the bricks on the racks. The above action lasts about one-half hour, at the end of which time the exhaust end of the drier has become fairly well heated. The entrance of cold air 45 through the monitors at the outlet end is
- objectionable, as in winter time this causes rapid condensation, and where the drier building is equipped with glass windows in the monitor, this condensation would drip onto the drier racks and would have to be 50 taken care of by the application of increased heat. During the first half or three-quarters of an hour, tests made show that little or no air flows along or through the piles of brick and it is only after the drying apparatus becomes thoroughly heated that the current of warm air passes up through the stacks of brick on either side. Even after the drier became thoroughly heated, tests show that very little air passes through the 55 drier, and, within the drier itself, the air becomes practically motionless, particularly in the vicinity of the stacked brick.
- In my present invention I have obviated the objections noted above in existing types 60 of apparatus and have produced a drier in which the ventilators insure a constant flow of exit air and which will not permit the back flow of cold air from the monitor, as in the present type of apparatus. Also, I 65 have produced a device by means of which the amount of air passing through the drier, and particularly the lower part thereof, is controlled.
- In carrying out my invention, I have provided along the sides of the drier house, 70 inlet pipes through which air may flow at a plurality of points, and adjacent to each side wall of the drier I provide baffle plates which direct the air inwardly and upwardly 75 with regard to the drier building. Extending lengthwise of the drier building and suitably spaced from each other and form the side walls I arrange pipe racks on which the brick to be dried are placed, as is usual. 80 The side wall of the drier house, the baffle plates above referred to, and the drier racks form a chamber into which the air is forced through the inlet pipes arranged at the lower portion of the side walls so that the 85 only exit from such chamber for the heated air is around and through the bricks resting on the racks.
- The principal object of my invention, 90 therefore, is an improved pipe rack drier. 100

Another object of my invention is an improved means for controlling quantities of air in the drier.

A further object is an improved means for directing the flow of air over the bricks in the racks prior to the exit of such air through the ventilators.

In the accompanying drawings illustrating a preferred embodiment of my invention,

Fig. 1 is a side elevation of a portion of a drier building to which my invention has been applied;

Fig. 2 is a sectional plan view of Fig. 1 on the line 2—2, and

Fig. 3 is a sectional end elevation of Fig. 1 on the line 3—3.

Referring to the drawings, 9 designates generally a drier building composed of side walls 10 and 11 tied together adjacent their top ends by beams 12, and supporting a roof 13, on which is mounted at suitable intervals ventilating monitors 14. In the side walls at suitable intervals are placed windows 15 and along the lower edge of the wall 11 at suitable intervals are inlet ports 16 and through which air may flow, as indicated by the arrows shown in Fig. 3. Beneath the wall 11 and below the floor 17 of the drier building 9, and extending transversely of such building, are conduits 18, which conduits terminate adjacent the side wall 10 in inlet pipes 19, there being one of such conduits 18 and inlet pipes 19 for each of the inlet ports 16. Suitable means is provided for forcing air through the ports 16 and conduits 18 but as such means forms no part of my present invention, it has not been illustrated and will not be further referred to.

Centrally located in the building 9, and extending longitudinally thereof, is an endless conveyor arrangement 20, on which a plurality of pallets 21 carrying brick 22 may be moved into the building and loaded on the pipe racks designated generally by the reference numeral 23. The pallets 22 resting on the pipes in the rack 23 form a plurality of shelves under and over which the air passes in coming from either the ports 16 or the inlet pipes 19. Extending from the side walls 10 and 11 and inwardly and upwardly therefrom, with their outer ends resting on the top of the pipe racks 23, are baffle plates 24 and which act as deflectors to force the heated air inward toward the center of the building 9. As the heated air will naturally rise, and being under pressure, even though slight, such air will follow the direction of the arrows shown in Fig. 3, passing through the drier and around the brick 22 and thence follow a general upward direction and pass out through the monitors 14.

By having a plurality of ports 16 and inlet pipes 19, and having such pipes arranged

at the lower and outer sides of the building 9, and providing the deflectors or baffle plates 24 in connection with the drier racks 23, I insure that every particle of air passes through the driers and around the bricks 22 ⁷⁰ thereon and such air will pass upward and out through the monitors 14.

There will be a region on either side of the ascending column of hot air under the roof structure 13 in which the air will be ⁷⁵ practically dead or motionless and also surrounding the endless conveyor arrangement 20 is another region of dead or motionless air. Such regions will, however, have no effect on the efficiency of the apparatus and ⁸⁰ act rather as insulators to enclose the moving volume of heated air. The moisture taken from the brick 22 by the heated air passes, therefore, in a solid column up through, and out of the building 9 and, therefore, such construction will prevent the condensation that now takes place in present types of buildings. Further, as all parts of the drier are heated practically simultaneously, there is no inrush of cold air from the monitors ⁸⁵ located at the exhaust end of the building, and, therefore, the occasional freezing of brick at the exhaust end due to condensation is positively ⁹⁰ prevented.

Having thus described my invention, what I claim as new is:

1. An improved drying apparatus for brick and the like comprising a pipe rack drier for holding a plurality of layers of brick thereon, an air inlet, a deflector extending from a point above the inlet upward and to the top of the pipe rack drier whereby the air is prevented from rising above such deflector, said deflector guiding the air from the inlet through the pipe rack drier and ¹⁰⁰ around the brick therein.

2. An improved drier for brick and the like comprising a drier shed, pipe rack driers arranged at either side of the medial line thereof and extending longitudinally of said building, deflectors resting on top of each of said driers and extending outward and downward to the adjacent wall of the building, air inlets arranged along each wall adjacent to the bottom thereof whereby air ¹¹⁰ passing thru such inlets will be directed by the deflector upward and inward with respect to said drier house and passing thru the driers and upward to the center of the drier house.

3. An improved drying apparatus for brick and the like comprising a drier house, pipe rack driers arranged in said building on either side of the central line thereof and spaced apart from the walls and from each other, deflectors resting on top of each of said driers and extending outwardly and downwardly and having their outer ends supported on the adjacent walls, a plurality of air inlets arranged along one of said walls ¹²⁵ ¹³⁰

adjacent to the bottom thereof, a plurality of air conduits arranged beneath the floor of said drier house and terminating in the exit adjacent the other of said walls and at the lower end thereof, whereby air will be delivered simultaneously through the orifice in the first said wall and through the

outlets of the conduits and will be constrained to move inward and upwardly through the pipe rack driers by the afore-¹⁰ said deflectors.

In testimony whereof, I have signed my name to this specification.

CLAUD E. FULLER.
